UNITED STATES PATENT OFFICE.

EDWARD A. DE STEIGER, OF LA SALLE, ILLINOIS.

FRUIT-JAR.

SPECIFICATION forming part of Letters Patent No. 336,800, dated February 23, 1886.

Application filed September 1, 1885. Serial No. 175,869. (Model.)

To all whom it may concern:

Be it known that I, EDWARD A. DE STEIGER, a citizen of the United States, residing at La Salle, in the county of La Salle and State of Illinois, have invented certain new and useful 5 Improvements in Fruit-Jars; and I do declare the following to be a full, clear, and exact description of the invention, such as will enable others skilled in the art to which it appertains 10 to make and use the same, reference being had to the accompanying drawings, and to letters or figures of reference marked thereon, which form a part of this specification.

My invention relates to fruit-jars; and it 15 consists in the construction and novel combination of parts, as will be hereinafter more fully described, and particularly pointed out in the claim.

The object of the invention is to provide a 20 simple and perfect fastening which shall render the vessel perfectly air-tight, and which will admit of a more simple and practical construction of a glass cover and wire fastener than has heretofore been attainable.

25 In the drawings, Figure 1 is a detached view of the cover. Fig. 2 is a detached view of the wire fastener. Fig. 3 is a perspective view of the shoulder of the jar; and Fig. 4 is a perspective view of the jar with cover attached.

30 In the accompanying drawings, A designates a glass jar, and d is the shoulder of the same, in which are formed the recessed bearings e molded in the glass at equal distances apart.

35 a designates the cover, which is made of pressed glass or of pressed metal, and is provided with a center-pin, b, and two inclined arc-shaped ridges, c c, each extending half-way round or a lesser distance on the upper face of 40 the cover, near the edge of the same, and equally distant apart.

f designates a wire fastener coiled at its middle to fit over the center-pin b.

g is a suitable gasket or packing-ring consisting of rubber or other elastic packing material, which rests upon the shoulder of the jar outside of the neck.

I attach importance to the cover having a

milled periphery, and to the fact that it is not necessary to touch the wire or bar in fastening and unfastening the cover, it only being necessary to turn the cover alone to engage and disengage the inclined ridges from the rod.

It has heretofore required great care in devices of this character where a rotative fastening-bar has been used to prevent accidental displacement of the same, as should the said bar become engaged by anything, so as to move it in the direction of the incline of the ridges, 60 the whole device would become inoperative by the loosening of the cover. These objections are obviated by my construction, as the fastening-rod cannot be moved in either direction until the cover has first been turned.

65 To use the jar, the packing-ring is first placed on the shoulder of the jar. The wire fastener is then placed on the cover, the coil or loop of the wire encircling the center-pin in the cover. The cover is then placed on the 70 mouth of the jar, so that the hook ends of the wire will be directly under the recessed bearings. The cover, which has a milled periphery, is then turned to the right, tightening as the inclined ridges press under the wire, and thus 75 securing the cover tightly in place.

Having thus described my invention, what I claim, and desire to secure by Letters Patent, is—

80 The combination, with a jar having recessed bearings at opposite points, of a cover having a milled periphery, inclined ridges on its upper side, and a central vertical integral stud, and a rod coiled to form an eye to receive the said stud, and having its opposite ends bent 85 downwardly and inwardly to engage the recessed bearings in the jar, whereby the said rod may remain fixed with relation to the jar when the cover is turned to fasten and unfasten the same, substantially as specified.

90 In testimony whereof I affix my signature in presence of two witnesses.

EDWARD A. DE STEIGER.
